(57) **CLAIM**

The ornamental design for a syringe connector, as shown and described.

DESCRIPTION

1. Syringe connector

1.1: Front view of the syringe connector;

1.2: Back view thereof;

1.3: Right view thereof;

1.4: Left view thereof;

1.5: Top view thereof;

1.6: Bottom view thereof;

1.7: Cross-sectional view along line 1.7-1.7 shown in reproduction 1.5;

1.8: Cross-sectional view along line 1.8-1.8 shown in reproduction 1.5;

1.9: Perspective view thereof; and

1.10: Reference perspective view thereof.

This article is a syringe connector, as shown in reproductions; the views including the cross-sectional views (1.7-1.7 line cross-sectional view and 1.8-1.8 line cross-sectional view) specify the portions to be sought as partial design right; reproduction 1.10 is reference perspective view of the article. The broken line showing of the syringe connector is for the purpose of illustrating portions of the "article" and form no parts of the claimed design.

1 Claim, 10 Drawing Sheets
